(57) **CLAIM**

The ornamental design for a keypad door lock, as shown and described.

DESCRIPTION

FIG. 1 is a front side perspective view of a keypad door lock showing my design;

FIG. 2 is a rear side perspective view of the keypad door lock as shown in FIG. 1;

FIG. 3 is a front elevational view of the keypad door lock as shown in FIG. 1;

FIG. 4 is a rear elevational view of the keypad door lock as shown in FIG. 1;

FIG. 5 is a left side elevational view of the keypad door lock as shown in FIG. 1;

FIG. 6 is a right side elevational view of the keypad door lock as shown in FIG. 1;

FIG. 7 is a top plan view of the keypad door lock as shown in FIG. 1; and,

FIG. 8 is a bottom plan view of the keypad door lock as shown in FIG. 1.

The broken lines, shown in the drawings, indicate portions of a keypad door lock which form no part of the claimed design.
